UNITED STATES PATENT OFFICE.

SAMUEL E. ROSS AND PHILIP H. BOWLSBY, OF WALKERVILLE, ONTARIO, CANADA.

DISPENSING DEVICE.

Application filed March 21, 1927. Serial No. 177,002.

This invention relates to dispensing devices and the object of the invention is to provide a device for dispensing paste from a tube.

5 One of the particular objects of the invention is to provide an arrangement whereby the tube is sealed except when paste is being dispensed from the tube.

Another object of the invention is to provide a paste dispenser in which the paste tube is arranged to turn on a pivot for dispensing the paste, the sealing member being turned on its pivot to seal the paste tube as it is turned back to closed position.

15 A further object of the invention is to provide a device of the character described in which the paste tube is locked in the sealed position and must be released before dispensing paste therefrom.

20 These objects and the several novel features of the invention are hereinafter more fully described and claimed and the preferred form of construction by which these objects are attained is shown in the accompanying drawing in which—

Fig. 1 is a side elevation of a dispensing device embodying our invention.

Fig. 2 is a plan view of a portion of the dispenser.

30 Fig. 3 is a bottom view of the portion of the dispenser shown in Fig. 2.

Fig. 4 is a section taken on line 4—4 of Fig. 2.

35 Fig. 5 is a section taken on line 5—5 of Fig. 3.

As shown in Fig. 1 the device comprises a sheet metal base 1 having two upwardly extending standards 2 and 3 shown in section in Fig. 4. A member 4 is provided having a stem 5 extending through the standard 2 and which is preferably squared at the end and a disc 6 is provided with a squared aperture at the center fitting over the squared end of the stem 5. This disc is secured in place by 40 the screw 7 which extends through a washer 8 and into the end of the stem 5. This disc is provided with a C shaped rib 9 as shown in Fig. 3 and a pin 10 is secured in the outer edge of the disc 6 centrally between the ends 45 of the rib 9.

50 As shown in Figs. 1 and 4 a member 11 is provided having a stem 12 extending through the standard 3 and this stem 12 is preferably provided with a squared end extending into the base 1. A member 13 is 55 provided with a squared aperture fitting the squared end of the stem 12 and a screw 14

extends through a washer 15 and is threaded into the stem 12 to secure the member 13 thereto. This member 13 is shown more particularly in Fig. 3 and is provided with two 60 arcuate faces 16 and 17 and with a slot 18 in which the pin 10 on the disc 6 is adapted to engage similar to a Geneva action. As shown in Figs. 1, 2 and 4 a discharge nozzle 19 is provided into which the threaded end of the paste tube 20 is threaded. The nozzle 19 is provided with a longitudinal aperture 21 through which the paste from the tube 20 may pass and this nozzle is secured in the member 4 by means of a threaded sleeve 22 which is 65 threaded into an aperture provided therefor in the member 4. The member 11 is provided at the upper end with a cylindrical casing 23 in which a member 24 is longitudinally movable by the coiled spring 25. The end of the 70 casing is closed by a plug 26 and the member 24 is provided with a cork seat 27 for the end of the nozzle 19. In order to maintain the nozzle 19 in the sealed position shown in Fig. 4 the disc 6 is provided with a notch 28 in 75 which a depression 29 in a flat spring 30 engages. This flat spring 30 as shown in Figs. 3 and 5 is provided with a lug 31 which is soldered to the under side of the base 1 to secure the spring in position. The depression 29 and the notch 28 are rounded so that when the tube 20 is turned by hand to turn the member 4 and disc 6 secured thereto the lug 29 will readily pass out of the notch 28. This 80 depression 29 tends to hold the parts in the 85 position shown in full lines in Fig. 2.

The base 1 is secured to a wall with the parts in the position shown in full lines in Fig. 2. To use the device the paste tube 20 is turned by hand to the position shown in dotted lines in Fig. 2. This turns the disc 6 so that the pin 10 passes out of the slot 18 thus turning the member 13 to the dotted position shown in Fig. 3 and moving the pin 10 to the dotted position. This movement causes the arcuate face 17 of the member 13 to engage the C shaped rib 9 as shown in Fig. 3 and by this arrangement the casing 23 and closure member 24 are turned as the nozzle 19 is turned. As the tube is turned back to the position shown in full lines in Fig. 2 the pin 10 is moved into the slot 18 of the member 13 and turns the member 13 back to the position shown in full lines in Fig. 3 at which time the depression 29 engages in the notch 28 and locks the parts in the closed position. It will be noted that as the nozzle 19 is turned 90 95 100 105 110

from the dotted position in Fig. 2 to the position shown in full lines in said figure that the end of the nozzle engages in the cork seat 27 and moves the member 24 back slightly 5 against the tension of the spring 25. The spring 25 therefore provides a pressure to hold the cork seat 27 over the end of the nozzle 19 to prevent further discharge of paste. When this device is used for tooth paste the 10 turning of the device to the open position allows the paste to be discharged through the aperture 21 onto the tooth brush and when the parts are turned back again further discharge from the paste tube is automatically prevented. While this device is intended particularly for dispensing tooth paste or shaving cream it may be used wherever paste is to be dispensed from a collapsible tube.

From the foregoing description it becomes 20 evident that the device is very simple and efficient in operation, will not easily get out of order, allows ready replacement of the paste tube when empty and provides a device which accomplishes the objects described.

25 Having thus fully described our invention, its utility and mode of operation, what we claim and desire to secure by Letters Patent of the United States is—

1. In a dispensing device, a base, a pair 30 of members rotatably mounted in the base, a nozzle supported in one of the members, the nozzle being adapted for threaded relation with the discharge end of a paste tube, a spring pressed nozzle closure member supported in the other rotatable member and normally closing the nozzle, a disc secured to the rotatable member in which the nozzle is supported, a slotted member secured to the other rotatable member, a pin extending from the 35 disc and adapted to engage in the slotted member to turn the slotted member to a limited extent as the disc is turned, the disc being provided with a notch and a flat spring having an end engaging in the said notch when 40 the nozzle is in the closed position.

2. In a dispensing device, a base, a pair

of members rotatably mounted in the base, a nozzle supported in one of the members, the nozzle being adapted for threaded relation with the discharge end of a paste tube, a 50 spring pressed nozzle closure member supported in the other rotatable member and normally closing the nozzle, a disc secured to the rotatable member in which the nozzle is supported, a slotted member secured to the other 55 rotatable member and a pin extending from the disc and adapted to engage in the slotted member to turn the slotted member to a limited extent as the disc is turned.

3. In a dispensing device, a base, a pair of 60 members rotatably mounted in the base, a nozzle secured to one of the members, the nozzle being adapted for threaded relation with the discharge end of a paste tube, a nozzle closure member supported in the other 65 rotatable member, a spring tending to hold the nozzle closure member in position to close the nozzle, the two rotatable members being connected together so that when the nozzle is turned the nozzle closure member is turned 70 away from the nozzle and as the nozzle is returned the closure member is moved into sealing engagement with the nozzle.

4. In a dispensing device, a base, a pair of 75 members rotatably mounted in the base, a nozzle secured to one of the members, the nozzle being adapted for threaded relation with the discharge end of a paste tube, a nozzle closure member secured to the other rotatable member and normally closing the nozzle and 80 means whereby rotation of the nozzle and its support in one direction turns the nozzle closure member out of contact with the nozzle and subsequent rotation of the nozzle and its support in the opposite direction moves the 85 closure member into engagement with the nozzle.

In testimony whereof we sign this specification.

SAMUEL E. ROSS.
PHILIP H. BOWLSBY.
